CLAIM

The ornamental design for an electronic device storage cart, as shown and described.

DESCRIPTION

FIG. 1 is a front perspective view of an electronic device storage cart embodying our novel design;

FIG. 2 is a rear perspective view of an electronic device storage cart embodying our novel design;

FIG. 3 is an elevation view of the front of the electronic device storage cart of FIG. 1;

FIG. 4 is an elevation view of the back of the electronic device storage cart of FIG. 1;

FIG. 5 is an elevation view of the left side of the electronic device storage cart of FIG. 1;

FIG. 6 is an elevation view of the right side of the electronic device storage cart of FIG. 1;

FIG. 7 is a top plan view of the electronic device storage cart of FIG. 1; and,

FIG. 8 is a bottom plan view of the electronic device storage cart of FIG. 1.

The broken lines shown in the drawings are for illustrative purposes only and form no part of the claimed design.
